UNITED STATES PATENT OFFICE

161,709

AUTOMOBILE READING LIGHT

Orval W. Rahn, Chicago, Ill., assignor to Patent License Corporation, Chicago, Ill., a corporation of Illinois

Application March 8, 1950, Serial No. 8,390

Term of patent 14 years

(Cl. D48—32)

To all whom it may concern:

Be it known that I, Orval W. Rahn, a citizen of the United States, residing at Chicago, in the county of Cook and State of Illinois, have invented a new, original, and ornamental Design for an Automobile Reading Light, of which the following is a specification, reference being had to the accompanying drawing, forming a part hereof.

In the drawing:

Fig. 1 is a top plan view of an automobile reading light showing my new design;

Fig. 2 is a front elevational view thereof; and

Fig. 3 is a side elevational view partly in cross section through the center of the lens.

The dominant features of my design reside in the portions shown in solid lines.

I claim:

The ornamental design for an automobile reading light, substantially as shown and described.

ORVAL W. RAHN.
